UNITED STATES PATENT OFFICE.

FRANK C. DORMENT AND GEORGE C. McVOY, OF DETROIT, MICHIGAN.

ATOMIZER.

No. 852,828.

Specification of Letters Patent.

Patented May 7, 1907.

Application filed November 26, 1906. Serial No. 345,190.

To all whom it may concern:

Be it known that we, FRANK C. DORMENT and GEORGE C. McVOY, citizens of the United States of America, residing at Detroit, in the county of Wayne and State of Michigan, have invented certain new and useful Improvements in Atomizers, of which the following is a specification, reference being had therein to the accompanying drawings.

This invention relates to improvements in ozonizers, atomizers or similar devices and one of its objects is to provide a very simple and cheap construction which is of such a size and shape that the operator may manipulate and hold the same with one hand.

A further object is to provide an instrument which is very compact in its construction and which has its discharge tube so arranged that it may be turned into engagement with the pump plunger and utilized to hold the same pressed inward so that less space will be taken up in packing.

It is also an object of the invention to so arrange the parts as to adapt the device to hold but a small quantity of the medicament at one time, thus preventing the liquid from becoming stale or rancid from long standing, and to so construct the device that all of the medicament contained therein may be atomized out.

Other objects of the invention are to provide a cheap and simple construction in which the parts may be readily taken apart for cleaning and repair, and to provide a very simple, cheap and efficient pump valve and other new and useful features in the construction, arrangement and combination of parts, all as hereinafter more fully described, reference being had to the accompanying drawings, in which:—

Figure 1 is a side elevation of a device embodying the invention and showing the parts in the position in which they are placed for packing the instrument in the smallest compass; Fig. 2 is a central vertical section of the same with its parts in extended position; Fig. 3 is a side elevation illustrating the manner in which the device is held in use and operated with one hand; Fig. 4 is a detail of the pump valve showing an elevation of the lower side of the piston head.

As shown in the drawings 1 is a glass cup or receptacle for the liquid medicament which is formed with a deep annular depression 2 or groove in its side wall and provided with screw-threads at its upper end to re-

ceive a screw-cap 3 formed of sheet metal. A sheet metal disk or plate 4 of a diameter to fit within the cap is placed therein between it and the upper edge of the cup with a washer or gasket 5 of leather or other suitable material between the disk and edge to make a tight joint, and secured to or formed integral with the disk and depending within the axis of the cup is a tubular member opening through the disk at its upper end and forming a sheet metal pump cylinder 6 having a closed lower end or head 7 which is depressed to form a shoulder 8 in the cylinder to engage and limit the stroke of the piston and to also form an internal chamber 9 below the piston when the same is at the inner limit of its stroke.

The cylinder is suspended within the cup with its inner end at a short distance from the bottom of said cup and secured to or formed integral with its lower end or head and extending diametrically across the same, is a tube 10, one end of which extends laterally from the cylinder with a slight downward curve and opens near the bottom adjacent to the point where the side and bottom of the cup meet.

A very small hole 11 is provided in the cylinder head opening into the extreme opposite closed end of said tube and directly opposite in the outer wall of the tube is a large hole 12.

In the axis of the screw-cap 3 is a flanged opening within which is guided a tubular stem or piston rod 13 formed with a head or finger piece 14 on its outer end. This head is formed by flanging or turning the metal of the tube outward and securing a convex disk of sheet metal to the flange by turning the edge of the disk over and beneath the edge of said flange.

Rigidly secured to the tubular piston rod or stem at a short distance from its inner end which is externally screw-threaded, is the piston 15, consisting of a disk of sheet metal turned upward at its edge to form a peripheral stiffening flange 16 and secured to the lower face of said piston by a disk washer or nut 17 is the packing leather 18 with its downwardly turned edge confined between the edge of the washer and the cylinder to make a tight joint.

A valve 19 to close the lower end of the tubular piston rod is provided and consists of a disk 20 of suitable flexible material such as thin leather, which is held in place over the

end of the tube, by forming said leather disk with integral laterally and oppositely extending arms or strips 21 cut from the same flexible material and securing the ends of these strips within radial slots 22 cut inward from the edge of the washer 17 by passing said ends through the slots and screwing the washer upon the stem downward against the piston with said ends between, the free portion of said strips being left of such a length that the disk is permitted to move away from the end of the tube slightly upon the outward movement of the piston and permit the air admitted to the stem through a small opening 23 in its outer end, to enter the interior of the cylinder. A coiled spring 24 interposed between the piston and bottom of cylinder normally holds said piston at the extreme outer end of its stroke, and a series of holes 25 in the cap 3 permits the free entrance and exit of the air to the cylinder above the piston.

In the cap 3 at one side of the piston is a flanged opening and a corresponding opening 25 is provided in the disk 4 within which latter opening is rigidly secured a tube or thimble 26 extending upward through the flanged opening in the cap and downward a short distance within the cup. A discharge or delivery tube 27 having a tapering end to fit within the outer end of the thimble is firmly held in place therein by the frictional engagement of the tapered end with the thimble and the opposite end of said tube is provided with a suitable nasal tip 28, the tube being bent to the proper angle to insert the tip in the nostril of the user when the cup is held in the proper position for use, as shown in Fig. 3. This bend is such that the body of 40 the tube extends substantially at right angles to the tapering end and therefore when the piston stem 13 is forced inward and said tube turned in its thimble to extend across the finger piece of the stem, said stem will be held 45 in that position by the tube and the device may be packed in its assembled state in a small space.

As illustrated in Fig. 3, the operator grasps the device in one hand, placing his thumb on 50 the bottom of the cup and his first finger upon the finger piece of the stem, and tilting the device so that the medicament flows into that angle of the cup into which the laterally extending end of the tube 10 extends presses 55 the piston inward. This inward movement of the piston forces the air confined in the cylinder by the valve 19, outward through the holes 11 and 12 and in passing through said holes draws a quantity of the medicament up through the tube 10 and discharges 60 it into the cup together with the air in a fine spray and this medicament laden air is forced by the pressure thus created in the cup, outward through the discharge tube and 65 tip. The device is thus adapted to contain

only enough medicament for a few treatments as a larger quantity would cover the holes 11 and 12 and therefore the medicine never becomes stale or spoiled from standing too long, and by reason of the tilting of the 70 cup and the tube 10 extending laterally into the angle, all of the medicament may be atomized out.

Only a small amount of medicament being contained in the cup, said cup may be made 75 of convenient size to hold in the hand and the air pump placed within it, thus making a very compact and convenient device.

If the atomizer be used by a lady or child having small hand, that person may place 80 her thumb within the depression or groove 2 in the side of the cup.

By the arrangement of cap and disk which is tightly held thereby, the cylinder is centered and firmly held in the cup and the parts 85 may be quickly and easily detached. The simplicity and cheapness of the construction of valve and other parts also add to the novelty of this invention.

Having thus fully described our invention 90 what we claim is:

1. In a device of the character described, the combination with a medicament receptacle, of a cylinder supported within the receptacle, a piston in the cylinder, means for actuating the piston, and a tube secured to the cylinder and opening at one end into the receptacle near its bottom and provided with a hole near its opposite end opening into the cylinder and a second hole opposite the first 100 hole opening into the receptacle.

2. In a device of the character described, the combination with a medicament receptacle, of a cylinder having a closed inner end supported upon the top of the receptacle and projecting downward in the axis thereof to a point adjacent to its bottom, a piston in the cylinder having a stem extending outward through the outer end thereof, and a tube secured to and extending across the inner 110 closed end of the cylinder and provided near one side of the cylinder with a hole opening through the end of said cylinder and a second hole of larger diameter opening into the receptacle opposite said first hole and said tube 115 being extended laterally from the cylinder at one end into the angle formed by the meeting of the side and bottom of the receptacle.

3. In a device of the character described, the combination with a medicament receptacle and an air pump connected therewith having a longitudinally movable piston stem projecting therefrom, of a delivery tube revolvably connected with the receptacle and adapted to be turned into engagement with 125 the stem to hold the same within the cylinder of the pump.

4. In a device of the character described, the combination with a medicament receptacle, of a cylinder extending into the recepta- 130

- cle, a piston in said cylinder, a stem on the piston extending outward through the end of the cylinder, a spring to normally hold the piston at the outer end of its stroke with the stem projected, and a delivery tube revolvably attached to the receptacle and adapted to be turned into engagement with the stem to hold the same within the cylinder against the action of said spring.
- 5 5. In a device of the character described, the combination with a medicament receptacle, of a cap to close said receptacle and provided with an axial opening, a disk adapted to fit within the cap and be secured thereby between it and the upper end of the receptacle, a cylinder secured to and supported by the disk within the axis of the receptacle, a piston in the cylinder, a stem on the piston extending downward through the opening 15 in the cap, and a delivery tube extending through the cap and disk.
- 6 6. In a device of the character described, the combination with a medicament receptacle, of a cylinder having an open outer end 20 supported within the receptacle, and extending downward therein, a cap to close the receptacle and outer end of the cylinder and provided with an axial opening at one side of the cylinder, a piston in the cylinder, a stem 25 on the piston extending outward through the axial opening in the cap, a spring to normally hold the stem projected, and a delivery tube having a tapering end to frictionally engage the side opening in the cap and bent substantially at right angles to the tapered end so 30 that when turned in said opening it will engage the outer end of the stem and hold the same within its cylinder against the action of said spring.
- 35 7. In a device of the character described, the combination with a medicament receptacle, of a cylinder supported to extend downward within the axis of said receptacle and having a closed inner end, a cap to close 40 the opposite end of said cylinder and the receptacle, a tube extending across the inner end of the cylinder having a closed and an open end and provided with opposed openings near its closed ends one of which communicates with the interior of the cylinder 45 and the other with the interior of the receptacle, a piston in the cylinder, a tubular stem attached to and extending through the piston and outward through the cap, a valve to 50 close the inner end of the stem, and a delivery tube opening through the cap into the receptacle.
- 55 8. In a device of the character described, the combination of a medicament receptacle, 60 and an air pump consisting of a cylinder, a valve disk to close the inner end of the stem

and provided with laterally and oppositely extending flexible portions, and means for securing the ends of said flexible portions to hold the disk adjacent to its seat on the end 65 of the stem and permit the free movement thereof.

9. In a device of the character described, the combination with a medicament receptacle, of a disk supported upon the upper 70 edge thereof having an opening near one side, a cylinder opening through said disk and extending downward in the axis of the receptacle, a cap adapted to close the receptacle and cover the outer end of the cylinder and 75 having an axial opening and an opening opposite the opening in the disk, a thimble secured in the opening in the disk and extending through the opening in the cap, a bent delivery tube having a tapered end engaging 80 said thimble, a piston in the cylinder, a tubular stem secured to and projecting through the piston and outward through the opening in the cap, a valve to close the inner end of 85 said stem, a spring in the cylinder between its inner end and the piston to actuate the piston in one direction, and a tube extending diametrically across the closed inner end of the cylinder, one end of said tube being closed and provided with opposed openings 90 through which the cylinder communicates with the receptacle and the opposite end being extended laterally into proximity with the angle of the receptacle formed by the meeting of its side and bottom. 95

10. In a device of the character described, the combination with a receptacle for medicament, of a cylinder, a piston in said cylinder, and a valve carried by the piston for admitting air below the same consisting of a 100 disk to set over and close the air inlet and having oppositely extending flexible portions, and a washer having radial slits to receive the free ends of said flexible portions and clamp the same between said washer and 105 the bottom of the piston, to hold the disk in place.

11. In a device of the character described, the combination of a medicament receptacle having an open top and a deep depression in 110 its side, a cap to close the receptacle, an air pump supported within the receptacle, and having a stem extending outward through and carried by the cap.

In testimony whereof we affix our signatures in presence of two witnesses.
